UNITED STATES PATENT OFFICE.

EMIL THIESLACK, OF BERLIN, GERMANY.

DIE-CASTING MACHINE.

Application filed May 18, 1925, Serial No. 31,182, and in Germany October 17, 1924.

My invention relates to die-casting machines and more especially to machines equipped with a ladle to receive the molten metal from which it is ejected by compressed air.

Die-casting machines have already been proposed in which the ladle is adapted to be tilted about a vertical axis so that in one of its final positions it is immersed in, and charged with, the molten metal, and in the other position it is connected to the injection nozzle so that the metal is forced into the ladle by the compressed air admitted through said nozzle. It has also been proposed to construct ladles which are not only adapted to be tilted about an axis but also to be displaced bodily while in the crucible.

These known machines involve the drawback that the tilting motion is not always performed satisfactorily as often the operation of the ladle is interfered with or prevented by adhering molten metal.

It is an object of my invention to overcome these drawbacks of the old machines altogether and to provide a die-casting machine which combines reliability of operation with ready assembling and dismantling and safe operation.

To this end, the ladle is not adapted to be tilted but to be displaced along an inclined path so as to be immersed into the molten metal in one of its positions, and charged, and to be connected to the injection nozzle in the other.

The ladle is operated by positive means, the ladle being carried on pins which may be provided with rollers to reduce friction, and are guided in slots of two plates at the sides of the machine frame. The ladle is preferably actuated by a rack and pinion drive, the rack being pivoted to the ladle at one end and supported on a stationary pin on which it may slide and about which it may rock.

The rack and pinion gear permits the ladle to be operated with a minimum of power and molten metal adhering to the guiding faces of the slots does not interfere with the operation of the ladle as the pins or rollers on which the ladle is moving have so much play in the slots that small accumulations of molten and hardened metal do not arrest their progress.

In machines of this kind it is also very important to prevent unintentional operation of the valve for the compressed air and

that the connection between the inlet and outlet for the compressed air should be positive.

The first condition is fulfilled by providing an automatic release in connection with the operating handle of the air inlet valve, the handle being disengaged from the valve spindle after the valve has been lifted from its seat to admit air for a casting and connected therewith only when the next casting is to be made. When the handle has been so disengaged, unintentional operation of the lever is not able to open the air inlet valve so that the accidents are avoided which are often caused by operation of the inlet valve out of time.

The groove for discharging compressed air is preferably milled into the valve spindle which greatly simplifies the construction.

In the drawings, a machine embodying my invention is illustrated by way of example.

Figure 1 is an elevation of the ladle, partly in section.

Figure 2 is an elevation of the air inlet valve, also partly in section.

Figures 3 and 4 are detail views illustrating modified connections of the handle for operating the air inlet valve, with said valve.

Referring now to the drawings, 1 is the crucible containing the molten metal which is heated by any suitable furnace, not shown. 2 is the ladle and 3, 3' are pins secured to the upper portion of said ladle. The pins are adapted to move in grooves 4, 4' of two lateral plates 5 which are secured to the frame, not shown, of the machine. It will be understood that only one of these plates is visible in the drawings. A rack 7 is pivoted about a pin 6 at the end of the ladle and supported on a check 8 in an upright 8' in which a pinion 9 with a crank 10 is arranged and adapted to mesh with said rack 7.

In the position shown in full lines in Figure 1, the ladle 2 is immersed in the crucible 1 and is charged with molten metal. When the ladle has been charged, the crank 10 is rotated and the ladle is pushed upwards on the grooves 4, 4' by means of the rack 7, as shown in dot-and-dash lines in Figure 1. In this position, the ladle is tightly connected to the die, not shown, and the molten metal may be ejected by the compressed air supplied to the pipe 11 by any suitable connection, not shown, from a pipe 14'.

The air inlet valve and its operating and releasing mechanism will now be described. The valve body 13 is seated at the top of a casing 14 to which compressed air is admitted through a pipe 12 which may be connected to any suitable source of compressed air. When the valve is opened air from 12 will enter the chamber 14 through the seat of the valve 13, and flow to the pipe 11 of the ladle 2 as described. The valve body is connected with a valve spindle 15 and the spindle 15 is connected with the operating lever 17 by means of a pawl 23. 19 is a spiral spring tending to hold the valve body 13 on its seat. 20 is a lug on the valve spindle which cooperates with two slots 21 in the wall of the sleeve in which the spindle 15 is guided.

The operation of my machine is as follows:

By depressing the lever 17 against the action of the spring 19 compressed air is admitted to the pipe 11 of the ladle 2 and the molten metal is ejected. On its downward motion, the connection of the lever with the spindle 15 is released by the lug 20 and the slot 21. Only when the lever 17 is returned to its upper end position its connection with the spindle 15 is re-established by the laminated spring 18.

In the position of the valve 13 shown in Figure 2, the air from the pipe 12 is discharged through the groove 16. It will appear that when the valve 13 is open the groove 16 becomes inoperative, as in this position it is not connected with atmosphere.

Modifications of the automatic release of the lever 17 are shown by way of example in Figures 3 and 4. It will appear from these figures that the spindle 15 of the valve 13 is connected with the lever 17 by means of a pawl 23 which is hinged to a disc 24 at the top of the spindle 15. When a lug 25 at the lever 17 and a lug 26 of the pawl 23 are in positive engagement the spindle 15 will be moved downwards. When the spindle is at the lower end of its stroke the lugs 25 and 26 are disengaged by corresponding lateral displacement of the pawl 23 so that the valve cannot be operated accidentally. Such operation is only possible after the lever 17 has resumed its upper end position.

In the modification shown in Figure 4 the lever 17 engages a groove 17' of the pawl 23 and the connection between the two parts is broken by a cam 27 when the valve has attained the lower end of its stroke.

It should be noted that with the novel type of ladle shown and described and by the way in which it is handled, the access of oxide to the die is absolutely prevented. Only pure and oxide-free metal can get into the die.

The formation of small quantities of oxide

on the surface of the molten metal in the crucible is inevitable. In the existing die-casting machines in which the ladle is moved slowly through the surface of the molten metal oxide will often get into the ladle. 70 By means of the drive shown in Figure 1, the ladle is rapidly immersed into the molten metal so that no oxide can get into it. On the contrary, it is charged with pure metal below the surface and the entrance of 75 impurities is absolutely prevented.

I claim:

1. In a die-casting machine a ladle, opposed pairs of inclined guides for slidably supporting the ladle so that the ladle may 80 be lifted and lowered through the guides to a position projecting outwardly from the ladle or in a submerged position within the ladle, and actuating means operatively connected with the inner end of the ladle for 85 imparting sliding movement to the ladle.

2. A die-casting machine including a frame, a crucible, a ladle adapted to be charged with molten material in said crucible, opposed parallel inclined guides for said ladle on the frame, means for imparting a sliding movement to the ladle to effect a lifting of the ladle along the guides to a position above the crucible and for lowering the 90 ladle into the crucible.

3. A die-casting machine including a frame, a crucible for containing molten metal, a ladle adapted to be charged with molten metal in said crucible, opposed pairs of trunnions projecting from the ladle the frame being provided with opposed pairs of parallel guide ways inclined upwardly toward the front end of the crucible and terminating in horizontal portions for accommodating the trunnions to effect supporting 100 of the ladle, and means for imparting a sliding movement to the ladle so that it may be elevated along the guide ways without being tilted to a position for discharging the 105 contents or lowering it into a submerged position within the crucible.

4. A die-casting machine as claimed in claim 3, wherein the means for imparting a sliding movement to the ladle includes a pinion supported in an elevated position, a rack having one end pivoted to the ladle, a lug positioned slightly beneath the pinion for ensuring of the meshing of the rack with the pinion, and means for rotating the pinion to move the rack and the ladle, substantially 115 as and for the purposes set forth.

5. A die-casting machine including a frame, a crucible adapted to contain molten metal, a ladle adapted to be charged with molten metal in the crucible, a frame including opposed pairs of upwardly and forwardly inclined guideways arranged parallel to each other and having the upper portions extending in substantial alignment 125 with each other, opposed trunnions project- 130

ing outwardly from the opposite sides of the ladle and slidably engaged with the guideways, so that when sliding movement is imparted to the ladle the latter will be lifted upwardly from the submerged position into a position of rest in the upper portions of the guideways so that the contents may be

ejected therefrom, and means for imparting a sliding movement to the ladle including a slidably and rockably mounted rack pivotally connected to the ladle. 10

In testimony whereof, I have signed my name to this specification.

EMIL THIESLACK.
